(57) **CLAIM**

We claim the ornamental design for a light field display, as shown and described.

DESCRIPTION

FIG. 1 is an isometric view, from the top, front, left of the light field display.

FIG. 2 is an isometric view, from the bottom, front, right of the light field display.

FIG. 3 is an isometric view, from the bottom, back, right of the light field display.

FIG. 4 is an elevation view from the front of the light field display.

FIG. 5 is an elevation view from the back of the light field display.

FIG. 6 is an elevation view from the right side of the light field display.

FIG. 7 is an elevation view from the left side of the light field display.

FIG. 8 is a plan view from the top of the light field display.

FIG. 9 is a plan view from the bottom of the light field display; and,

FIG. 10 is a cross-sectional view of the light field display along section 10-10 in FIG. 5.

The dashed broken lines in the figures depict portions of the light field display that form no part of the claimed design.

1 Claim, 9 Drawing Sheets
